Claims priority, application Japan Mar. 31, 1967

Term of patent 14 years

(Cl. D86—10)

FIG. 1

FIG. 2

FIG. 3

FIG. 4

FIG. 1 is an exploded perspective view of the roller for a hair curler of our design;

FIG. 2 is a top plan view thereof;

FIG. 3 is a side elevation thereof; and

FIG. 4 is an end elevation thereof.

The views from the opposite side end and the bottom view of the roller are identical with the corresponding views as shown. The dominant features of the design are the longitudinally and circumferentially lined portions of the cylindrical surface of the roller and the shape of the indentations on the end faces of the roller and the floral-like design thereon.

We claim:

The ornamental design for a roller for a hair curler, substantially as shown and described.
